UNITED STATES PATENT OFFICE.

GEORGE C. VAN RODEN, OF PHILADELPHIA, PENNSYLVANIA, ASSIGNOR TO
J. E. CALDWELL & CO., OF SAME PLACE.

DESIGN FOR A BADGE.

SPECIFICATION forming part of Design No. 20,748, dated May 19, 1891.

Application filed April 11, 1891. Serial No. 388,594. Term of patent 14 years.

To all whom it may concern:

Be it known that I, GEORGE C. VAN RODEN, a citizen of the United States, residing in the city and county of Philadelphia, State of Pennsylvania, have invented and produced a new and original Design for a Badge, of which the following is a specification, reference being had to the accompanying drawing, forming part thereof.

10 The leading feature of my design for a badge is a guidon having a field of different shades, and a staff from which the guidon apparently floats.

15 In the drawing, A designates a badge consisting of the guidon B and the staff C. The

field of the guidon is of different shades, as at D E, with a divisional line F between the same. The badge is more particularly designed for students, graduates, or others of the University of Pennsylvania, and the shades 20 of the field represent the "colors" of said institution.

I claim—

A design for a badge, substantially as shown and described.

GEORGE C. VAN RODEN.
